DENTAL INSTRUMENT

Roy L. Newman, 1023 Lundvall,
Rockford, Ill. 61107

Filed Apr. 17, 1969, Ser. No. 16,788

Term of patent 14 years

Int. Cl. D24—03

U.S. Cl. D24—1

FIG. 1 is a perspective view of a dental instrument embodying my new design;

FIG. 2 is a top elevational view thereof;

FIG. 3 is a side elevational view thereof, the other side being a mirror image thereof; and

FIG. 4 is an end view, on double scale, as seen from the right of FIG. 3.

The dotted line showing is for illustrative purposes only.

I claim:

The ornamental design for a dental instrument, substantially as shown and described.
